CLAIM

The ornamental design for a surgical stapler deck with tissue engagement cleat features, as shown and described.

DESCRIPTION

FIG. 1 is an enlarged perspective view of a surgical stapler deck with tissue engagement cleat features showing our new design;

FIG. 2 is a front elevational view of the staple cartridge housing of FIG. 1;

FIG. 3 is a rear elevational view of the staple cartridge housing of FIG. 1;

FIG. 4 is a first side elevational view of the staple cartridge housing of FIG. 1;

FIG. 5 is a second side elevational view of the staple cartridge housing of FIG. 1;

FIG. 6 is a top plan view of the staple cartridge housing of FIG. 1; and,

FIG. 7 is a bottom plan view of the staple cartridge housing of FIG. 1.

The broken lines immediately adjacent the shaded areas represent the bounds of the claimed design while all other broken lines are directed to environment and are for illustrative purposes only; the broken lines form no part of the claimed design.
